(57) **CLAIM**

The ornamental design for an object for interfacing with a computer program, as shown and described.

DESCRIPTION

The present design is an ornamental object that can be used as an input device for computer programs, and more particularly for a camera.

FIG. 1 is a front view of the object device in accordance with the design.

FIG. 2 is a bottom view of the object device of FIG. 1.

FIG. 3 is the side view of the object device of FIG. 1.

FIG. 4 is a top view of the object device of FIG. 1; and, FIG. 5 illustrates a perspective view of the object device of FIG. 1 being attached to the stick and handle that can be held by a hand.

The broken line showing of the hand is included for the purpose of illustrating usage and forms no part of the claimed design.
